UNITED STATES PATENT OFFICE.

VICTOR ALBERT LARSON, OF CHICAGO, ILLINOIS.

HUMIDIFYING DEVICE.

1,310,705.

Specification of Letters Patent. Patented July 22, 1919.

Application filed September 4, 1918. Serial No. 252,632.

To all whom it may concern:

Be it known that I, VICTOR A. LARSON, a citizen of the United States, and a resident of Chicago, in the county of Cook and State 5 of Illinois, have invented certain new and useful Improvements in Humidifying Devices, of which the following is a specification.

My invention is an improvement in humidifying devices, and has for its object to provide a device of the character specified especially adapted for use with radiators of steam and hot water heating plants, for humidifying the air heated by the radiator, 15 wherein a device is provided which may be easily placed and removed, and which will thoroughly moisten the heated air rising from the radiator.

In the drawings:

20 Figure 1 is a perspective view of the device in place;

Fig. 2 is a longitudinal vertical section;

Figs. 3 and 4 are sections on the lines 3—3 and 4—4, respectively, of Fig. 2, each view 25 looking in the direction of the arrows adjacent to the line;

Fig. 5 is a perspective view of one of the wick supports;

Fig. 6 is a perspective view of the device, 30 with the cover removed.

The present embodiment of the invention is shown in connection with a radiator 1 of ordinary type, and the humidifying device is seated upon the top of the radiator. The 35 said device comprises a trough 2 of a size to extend approximately the full length of the radiator and of a width somewhat less than the width of the radiator, the trough being adapted to seat upon the top of the 40 radiator, as shown in Figs. 2 and 3.

This trough is adapted to contain water, and a casing is arranged over and above the trough, to cover the same. This casing consists of a body and a perforated top, the body being a substantially rectangular frame consisting of sides 3 and ends 4, and it will be noticed, referring to Fig. 6, that the ends are cut away at their lower edges to approximately half the height of the 45 sides, and that the said ends have a flange 5 extending above the upper edges of the sides, the corners of the flanges being rounded. This body 3 is adapted to fit about the top of a radiator, with the lower edges 50 of the ends 4 resting upon the endmost sec-

tions of the radiator, and with the said ends contacting with the ends of the trough 2.

The cover 6 is a perforate sheet having its side edges curved to fit the rounded corners of the ends 4, to rest upon the said ends, 60 with the edges of the cover contacting with the upper edges of the side walls 3 of the body.

A pair of bars or plates 7 is arranged longitudinally of the body, the said plates 65 being secured to the ends 4 and being spaced apart from each other, as shown, and from the adjacent side walls. The plates are held in place in any suitable or desired manner, and a wick support is supported by each 70 plate. Each of these wick supports, as shown in Fig. 5, is composed of wire of suitable gage bent to form, and consists of three longitudinally extending members 8 and 9, and angular end members 10 connecting the 75 longitudinally extending members.

The longitudinally extending members 8 are at the ends of the angular end members 10, while the member 9 connects the angles of the said members 10. Thus a skeleton 80 frame is formed of angular shape, consisting of two portions having their planes at right angles, and these supports are supported by the said plates 7.

One of these portions rests upon the bar 85 or plate, with the other portion depending into the trough 2, and a wick 11 is supported by each of the said supports. The wicks are endless belts, passing around the members 8 and 9 of the frames, and the lower run 90 is held in place by the perforated plate 7. The wicks depend into the water in the trough.

In use, the device is arranged as shown in Figs. 1 to 3, inclusive, the trough 2 being 95 seated on the radiator section. The body 3—4 is then placed, after which the wick supports with the wicks in place are arranged on the plates 7. When now the cover 6 is placed in position the device is ready for 100 operation. The heated air rising upwardly from the radiator passes through the body of the casing and is thoroughly moistened by the water held on the wicks, passing out eventually through the perforations of the 105 cover 6. The device is applicable to any radiator and when not needed, as, for instance, when the radiator is not heated, may be removed for storage.

The plates or bars 7, in addition to sup- 110

porting the wick supports, hold the under portion of the wick taut and in angular position as shown in Fig. 3. The water passes up the wicks by capillary attraction continuously and continuously evaporates so long as there is water in the pan. In hard water, when the portion of the wick exposed to the air becomes clogged by deposits the wick may be moved to bring another part into contact with the water, where the deposits are redissolved.

I claim:

1. A device of the character specified, comprising in combination with a radiator, a trough adapted to seat upon the top of the radiator, a casing comprising a body frame open at its top and bottom and fitting over the trough, the sides of the body depending below the ends to permit said sides to extend below the bottom of the trough when the ends engage the top of the radiator, and a perforated cover resting upon the top of the body, said trough being adapted to contain water and the body having bars extending above the trough at each side of the center thereof, and wick supports upon the bars, each support carrying a wick and holding a portion of the wick in the water in the trough, each wick being in the form of an endless band mounted to move on the spring to bring different portions of the wick into contact with the water, each support having a skeleton frame having two portions extending at approximately right

angles with respect to each other, one of the 35 said portions resting upon the bar and the other depending therefrom.

2. A device of the character specified, comprising a trough adapted to seat upon the top of a radiator, a casing comprising a body frame open at its top and bottom and fitting over the trough, the sides of the body depending below the ends to permit said sides to extend below the bottom of the trough when the ends engage the top of the 45 radiator, and a perforated cover resting upon the top of the body, said trough being adapted to contain water and the body having bars extending above the trough at each side of the center thereof, and wick supports 50 upon the bars, each support carrying a wick and holding a portion of the wick in the water in the trough.

3. A device of the character specified, comprising a trough adapted to contain 55 water and to seat upon the top of a radiator, a casing for said trough comprising a body open at its bottom and having the sides of the body depending below the ends to permit said sides to extend down upon the sides 60 of the radiator when the ends engage the top thereof, wick supports carried by the casing, and wicks on the supports depending into the trough.

VICTOR ALBERT LARSON.
